UNITED STATES PATENT OFFICE.

EDWARD E. DAVIS, OF CHICAGO, ILLINOIS.

CENTERING-FORM APPARATUS FOR CONCRETE-FLOOR CONSTRUCTION.

Application filed November 30, 1925. Serial No. 72,166.

To all whom it may concern:

Be it known that I, EDWARD E. DAVIS, a citizen of the United States, residing at Chicago, in the county of Cook and State of Illinois, have invented new and useful Improvements in Centering-Form Apparatus for Concrete-Floor Construction, of which the following is a specification.

This invention relates to improvements in centering form apparatus for concrete floor construction and is here shown as embodied in a device especially adapted for constructing concrete floors in steel buildings between steel girders, or beams, with ceiling beams underneath.

Among the features of my invention is the provision of apparatus that may be readily put in place and removed without breakage, thus permitting repeated use of the same apparatus with a consequent saving in expense.

My improved apparatus is also so designed that it may be readily adjusted to different dimensions. For example, the same apparatus may be used between steel girders having different distances of separation. Because of this construction, it is not necessary to have so many different pieces of apparatus.

My improved centering form apparatus is also so constructed that it is light in weight, easily handled and adjusted, and yet strong, firm and tight. By the use of my apparatus, there is very little, if any, waste of concrete; and the resulting floor is smooth and neat in appearance, and strong and rigid. Other features and advantages of my invention will appear more fully as I proceed with my specification.

In that form of device embodying the features of my invention shown in the accompanying drawings—

Fig. 1 is a bottom plan view of a concrete floor constructed by the use of my apparatus; Fig. 2 is a view taken as indicated by the line 2 of Fig. 1; Fig. 3 is a view taken as indicated by the line 3 of Fig. 1; Fig. 4 is a view taken on the line 4 of Fig. 5, showing in side elevation one of the joist members forming a part of my apparatus and showing the same in place between two steel I-beams, and also showing in side elevation one of the pans in place; Fig. 5 is a broken top plan view of the apparatus in place between two steel I-beams; Fig. 6

is a view on an enlarged scale taken as indicated by the line 6 of Fig. 7; Fig. 7 is a top plan view on an enlarged scale taken as indicated by the line 7 of Fig. 6; Fig. 8 is a detail view of the spreader and supporting member taken as indicated by line 8 of Fig. 9; Fig. 9 is a sectional view taken as indicated by line 9 of Fig. 5; Fig. 10 is a view taken on line 10 of Fig. 6; and Fig. 11 is a broken top plan view showing spreaders arranged in oblique positions.

Briefly stated, in general, the apparatus comprises a plurality of joists adapted to be parallelly mounted between steel I-beams and supported by sliding bolts at the end 70 of each joist guided for reciprocal movement and having their outer ends adapted to rest on the upper surfaces of the lower flanges of said I-beams. Each joist carries on its upper edge a flat soffit board throughout its entire length. Mounted on the sides of the joists are cleats, or stirrups, adapted to support between each pair of joists a plurality of spreaders. Mounted on the spreaders between each pair of joists is an inverted 75 sheet-metal pan formed of four sections; each section having a vertical side face, a vertical end face, and a horizontal top face. The faces of the four sections of each pan are adapted to overlap each other so that the completed pan is closed at the top and the four sides, but open at the bottom, the overlapping faces making the same extensible both longitudinally and transversely. The spreaders carry uprights on the upper 80 ends of which rests a beam adapted to support the underside of the pan throughout its length at the center. Each of the spreaders has a vertical side and a horizontal side with the vertical side cut away near the 85 ends. A longitudinally arranged bar extending across the ends of the spreaders is adapted to bear against the inner surface of the lower edge of the vertical side of the pan and against the vertical side of the 90 spreader in order to hold the side face of the pan tightly against the edge of the soffit board. The apparatus is so arranged as to permit the easy removal of the spreaders, thereby also permitting the pans to be 95 dropped down between the joists, and the joists themselves removed.

I will now describe the apparatus more in particular. As shown in the drawings, 10, 10 indicate parallel I-beam girders form-

ing a part of the steel structure of a building. 11 indicates the completed concrete floor and 11^a the concrete ceiling beams formed on the underside of the floor proper and integral therewith. 10^a indicates the lower flange of the I-beam 10. 11^b indicates the concrete surrounding the I-beam 10 and formed integral with the floor 11 and ceiling beams 11^a. The parts so far referred to are possibly best shown in Figs. 1, 2 and 3, all of which show the completed floor with all the centering form apparatus removed.

In Figs. 4 to 11, inclusive, is shown the centering form apparatus and the method of putting it in place for the purpose of molding, forming, laying, or casting the completed floor. The apparatus includes a joist 12 preferably formed from a wooden timber, or plank, on edge, having on its upper edge a flat soffit board 13 extending substantially throughout its entire length. The ends of the joist 12 are provided with sliding bolts guided for reciprocal movement and adapted to support the joist between two I-beams 10. 14 (Figs. 6 and 7) indicates an inverted U-shaped guiding member passing over the joist 12. 15 indicates a U-shaped guiding member, nearer the end of the joist 12, passing under the joist 12. Both guiding members 14 and 15 have lateral flanges 16 provided with openings 17, through which the sliding bolts 17 are reciprocally slideable. As the joist 12 is supported upon the sliding bolt 17 by the web of guiding member 15 under the joist 12 and the web of guiding member 14 on the joist 12, the means for fastening the two guiding members to the joist are not required to sustain much strain and may be of any suitable kind, such as screws, nails, etc., and the guiding members therefore may be easily adjusted to any desired position along the joist. The inner ends 18 of the bolts 17 are turned downwardly below joists 12 to form operating handles. A slight swing of the handles at right angles to the bolt will cause the bolts to turn thus breaking the hold of the concrete and thereupon the bolts may be readily withdrawn without breakage of the concrete. The outer ends of the bolts 17 are adapted to rest on the upper surface of the lower flange 10^a of the I-beam 10 (see Figs. 6 and 7). When the outer ends of the sliding bolts 17 rest upon the lower flange 10^a of the I-beam 10, the weight of the joist is sufficient in itself to hold the sliding bolt in the guiding members.

The joist 12 is provided on each side with a plurality of cleats, or stirrups, 19, fastened by nails or other suitable means to the joist 12. As many of these stirrups are provided as may be necessary, depending upon the length of the joist. I have here shown each joist provided with three stirrups on each side.

Between each pair of joists are provided a series of spreaders 20 adapted to rest on the stirrups 19. One of these spreaders is probably best shown in Figs. 5, 9 and 11. The spreader is a member L-shaped in cross-section with a vertically disposed side 26 and a horizontally disposed side 29 and having the vertical side 26 cut away near the ends. When in position for forming the floor, the ends of the spreaders 20 rest on the cleats, or stirrups, 19, as shown in Figs. 5, 9 and 11. If the spreaders 20 are too long to be placed in a position at right angles to two joists 12, they may be arranged in oblique positions, the supporting cleats, or stirrups, 19 being attached to the joists at the proper places, as shown in Figs. 5 and 11. The spreaders 20 may be removed by knocking their ends off the cleats, or stirrups.

Each spreader carries substantially at its center a vertically adjustable U-shaped support 21 adapted to carry a pan-supporting member 27 here shown as comprising a plank set on edge. Each of the supports 21 (Fig. 9) is mounted on a horizontally bent top portion 39 of the upright 23 and rotatably secured thereto by a pin 22. The upright 23 is provided with a vertical series of perforations 37 adapted to register with perforations in the side 26 of the spreader 20 and is secured in the desired position by means of a bolt 24 and nut 25.

Between each pair of joists 12 is mounted a rectangular shaped pan formed of four sections preferably made of sheet-metal. These sections are indicated by 28, four of them forming one complete pan. Each of the sections 28 has a rectangular shaped horizontal top face, a vertical side face and a vertical end face. The four sections are placed together as shown in Figs. 4, 5 and 9, so that together they form a rectangular shaped pan closed at the top, sides and ends, but having the bottom open. By overlapping the top faces, side faces, and end faces of the various sections, the pan may be made longer or shorter, or narrower or wider, as desired. When in the desired position, the top faces of the various sections of the pan are rigidly secured to the supporting member 27 by nails, or other suitable means. In putting the apparatus in place, the joists 12 are first mounted between the I-beams 10, the stirrups 19 and spreaders 20 put in place, and then sheet-metal pans formed of the sections 28 placed on top of the spreaders 20 (Figs. 4, 5 and 9), with the lower edges of the side faces of the pan resting on the ends of the spreaders. In referring to a pan, I mean four sections placed together. Each pan is so adjusted that its sides 28^a will touch the edges of the soffit boards 13. The length of each pan is adjusted so that it will be about one inch longer on each end than the joists 12. In

Figs. 4, 5, 6 and 9, I have shown the joists, spreaders and pans in place. The supports 21 are so adjusted that the plank 27 will support the center of the pan throughout substantially its entire length (Figs. 9 and 11).

29 (Figs. 5 and 9) represents a beam, or plank, lying across the ends of the spreaders 20 against the side face 28^a of the pan and vertical side 26 of the spreaders 20 and serving to force the lower edge of the side face of the pan outwardly against the soffit board 13.

Under each of the I-beams 10 (Fig. 6) is supported a board 30 substantially wide enough to meet the ends of the joists 12 on the opposite sides of the I-beam 10. The supporting means comprises a rod 32 passing through openings 33 in the lateral flanges 16 of the guiding member 15 on joists 12 on opposite sides of the I-beam 10. Filler boards 31 are provided to fill the space between the lower edges of the end faces 28^b of the pans and the boards 30. Each of these boards comprises an upper part 31^a and a lower part 31^b. The upper part 31^a lies above the bolt 17 and the lower part 31^b lies below the bolt 17 and is nailed or otherwise suitably fastened to the edge of the board 30. The lower edge of the part 31^a is suitably notched with semi-circular notches in order to accommodate the bolt 17, and the upper edge of the part 31^b is similarly notched. The parts 31^a of the filler boards project up inside of the end faces 28^b of the pans. It will be noted that the board 30 together with the parts 31^b form a sort of trough under the I-beam 10.

The flanges 16 of the guiding members 14 and 15 have two series of openings. There may be any number of openings in each series. One series 34 is adapted to receive the sliding bolt 17, and the upper series 33 is adapted to receive the supporting rod 32. As an example, I have shown two openings in each series. The openings in each series are so spaced that the distance between centers of similar openings in each series is substantially the same. By this arrangement, the joist 12 may be raised or lowered by passing the bolt 17 through the proper opening in the series 34, and placing the supporting rod 32 in a corresponding opening in the series 33. By this arrangement, the distance between the lower surface of the lower flange 10^a of the I-beam 10 and the upper side of the board 30 will remain substantially the same, thus always securing the same thickness of concrete below the lower flange of the I-beam irrespective of the raising or lowering of the joists 12. Such raising or lowering of the joists 12 may be desirable in order to adapt the apparatus to I-beams 10 of different heights,

or in order to give different thicknesses of concrete 11 above the I-beam. With all such variations, however, it is desirable to have a uniform thickness of concrete under the lower flange 10^a, and this is accomplished as just described.

In the operation of the apparatus, the various parts are assembled as shown in Figs. 4 to 11 inclusive, and the concrete is then poured over the entire apparatus up to the level as indicated by 11^c in Fig. 4, this constituting the upper face of the floor. It will be seen that concrete will flow down between the pans on top of the soffit boards 13 to form the ceiling beams 11^a, and that concrete will also flow down around each of the I-beams 10 on top of the board 30 between the ends 28^b of the pans and the filler boards 31 to form the concrete 11 (Fig. 6) around the I-beam. After the concrete has set sufficiently, the spreaders 20 may be removed by knocking them off the cleats, or stirrups, until their ends clear the stirrups, whereupon they may be dropped down between the joists with the supporting boards 27, thus permitting the pans also to be taken down. The joists are removed by pulling in the bolts 17, thus permitting their ends to drop free from the I-beams.

While I have shown and described certain embodiments of my invention, it is to be understood that it is capable of many modifications. Changes, therefore, in the construction and arrangement may be made without departing from the spirit and scope of the invention as disclosed in the appended claims in which it is my intention to claim all novelty inherent in my invention as broadly as possible, in view of the prior art.

What I claim as new, and desire to secure by Letters Patent, is:

1. In apparatus of the character described; a joist; means for supporting the joist by its ends between parallel steel girders, said supporting means comprising guiding members on the joist and a sliding bolt slidable in said guiding members in a plane substantially parallel with the upper surface of the lower flange of one of said girders and resting on said surface.

2. In apparatus of the character described; a joist; means for supporting the joist by its ends between parallel steel girders, said supporting means comprising guiding members on the joist and a sliding bolt slidable in said guiding members and adapted to have its outer end rest on one of said girders and having its inner end bent downwardly and extending below said joist.

3. In apparatus of the character described; a joist; means for supporting the joist by its ends between parallel steel girders, said supporting means comprising spaced members having openings and a slidable bolt reciprocally movable therethrough

in a plane substantially parallel with the upper surface of the lower flange of one of said girders and resting on said surface.

4. In apparatus of the character described: a joist; means for supporting the joist by its ends between parallel steel girders, said supporting means comprising at each end of the joist an inverted U-shaped guiding member passing over the joist and a U-shaped guiding member near the end of the joist, passing beneath the joist; lateral flanges on said guiding members containing openings therein, and slidable bolts reciprocally movable through said openings and adapted to have their outer ends rest upon said girders.

5. In apparatus of the character described: a plurality of joists; means for supporting said joists by their ends between parallel steel girders, said supporting means comprising guiding members on the joists and sliding bolts slidable in said guiding members and adapted to have their outer ends rest on said girders; a trough adapted to be supported under one of said girders; and a supporting rod adapted to support the bottom of said trough under one of said girders, said supporting rod passing through said guiding members on joists on opposite sides of said girder.

6. In apparatus of the character described: a plurality of joists; means for supporting said joists by their ends between parallel steel girders, said supporting means comprising guiding members on each joist having openings and a slidable bolt reciprocally movable therein; a trough adapted to be supported under one of said girders; a supporting rod beneath the bottom of said trough passing through openings in said guiding members on joists on opposite sides of said girder, said guiding members having a plurality of openings adapted to receive the sliding bolt and the supporting rod, the distance between centers of the openings for receiving said bolt being equal to the distance between centers of the openings for receiving said supporting rod.

7. In apparatus of the character described: a plurality of joists; means for supporting said joists by their ends between parallel steel girders; cleats on the sides of said joists; a plurality of spreaders adapted to be supported by said cleats between each pair of joists, each spreader having a horizontal side and a vertical side and having the vertical side cut away near the ends; a pan adapted to be placed between each pair of joists resting on said spreaders; a beam lying across the ends of the spreaders between the vertical side of each spreader and the side face of the pan and adapted to force the lower edge of the side face of the pan outwardly against the joists.

8. In apparatus of the character de-

scribed; a plurality of joists; soffit boards on said joists; means for supporting said joists by their ends between parallel steel girders; cleats on the sides of said joists; a plurality of spreaders adapted to be supported by said cleats between each pair of joists, each spreader having a horizontal side and a vertical side and having the vertical side cut away near the ends; a pan adapted to be placed between each pair of joists resting on said spreaders; a beam lying across the ends of the spreaders between the vertical side of each spreader and the side face of the pan and adapted to force the lower edge of the side face of the pan outwardly against the soffit board.

9. In apparatus of the character described: a plurality of joists; means for supporting said joists by their ends between parallel steel girders; a plurality of spreaders adapted to be supported between each pair of joists; a pan adapted to be placed between each pair of joists resting on said spreaders; and a centrally arranged longitudinal supporting board carried by vertically adjustable members rotatably mounted on said spreaders and adapted to support the top face of said pan.

10. In apparatus of the character described: a plurality of joists; means for supporting said joists by their ends between parallel steel girders; cleats on the sides of said joists; a plurality of spreaders adapted to be supported by said cleats between each pair of joists, each spreader having a horizontal side and a vertical side and having the vertical side cut away near the ends; a pan adapted to be placed between each pair of joists resting upon said spreaders; a beam lying across the ends of said spreaders between the vertical side of each spreader and the side face of the pan and adapted to force the lower edge of the side face of the pan outwardly against the joist; and a centrally arranged longitudinal supporting board carried by vertically adjustable members rotatably mounted on said spreaders and adapted to support the top face of said pan.

11. In apparatus of the character described: a plurality of joists; means for supporting said joists by their ends between parallel steel girders; cleats on the sides of said joists; a plurality of spreaders adapted to be supported by said cleats between each pair of joists; a pan adapted to be placed between each pair of joists resting upon said spreaders; vertically adjustable uprights carried by said spreaders; supports rotatably mounted on said uprights and adapted to carry a horizontal pan-supporting member.

12. In apparatus of the character described: a plurality of joists; means for supporting said joists by their ends between

parallel steel girders; a plurality of spreaders adapted to be supported between each pair of joists; a pan adapted to be placed between each pair of joists resting on said spreaders, said pan comprising four sheet-metal sections each having a vertical side face, a vertical end face, and a horizontal top face, the four sections adapted to be placed together with their faces over-
lapping to form a pan having a top face, two side faces, and two end faces, and an open bottom; a centrally arranged vertically adjustable longitudinal supporting board carried by said spreaders and adapted to support the top face of said pan; means for rigidly securing the top of said pan to said supporting board.

13. In apparatus of the character described; a plurality of joists; means for supporting said joists by their ends between parallel steel girders; a plurality of spreaders adapted to be supported between each pair of joists resting on said spreaders; and a centrally arranged longitudinal supporting board carried by members rotatably mounted on said spreaders and adapted to support the top face of said pan.

14. In apparatus of the character described; a plurality of joists; means for supporting said joists by their ends between parallel steel girders; cleats on the sides of said joists; a plurality of spreaders adapted to be supported by said cleats between each pair of joists, each spreader having a horizontal side and a vertical side and having the vertical side cut away near the ends; a pan adapted to be placed between each pair of joists resting upon said spreaders; a beam lying across the ends of said spreaders between the vertical side of each spreader and the side face of the pan and adapted to force the lower edge of the side face of the pan outwardly against the joist; and a centrally arranged longitudinal supporting board carried by members rotatably mounted on said spreaders and adapted to support the top face of said pan.

15. In apparatus of the character described; a plurality of joists; means for supporting said joists by their ends between parallel steel girders, said supporting means comprising members carried by said joists adapted to rest on the lower flange of

the girder; a trough adapted to be supported under one of said girders; means carried by joists on opposite sides of a girder for supporting said trough; and means for adjusting the joist supporting means and the trough supporting means with respect to the joint whereby the height of the joist with respect to the bottom flange of the girder will be changed, but the position of the trough with respect to the lower flange of the girder will remain the same.

16. In apparatus of the character described; a plurality of joists; adjustable means for supporting said joists by their ends between parallel steel girders; a trough adapted to be supported under one of said girders; and adjustable means for supporting said trough, said trough supporting means carried by joists on opposite sides of a girder.

17. In apparatus of the character described; a plurality of joists; an adjustable means for supporting said joists by their ends between parallel steel girders; a trough adapted to be supported under one of said girders; and adjustable means for supporting said trough, said trough supporting means carried by joists on opposite sides of a girder; the adjustment of the joist supporting means and the trough supporting means with respect to the joist permitting raising or lowering of the joist with respect to the girder while maintaining the position of the trough with respect to said girder the same.

18. In apparatus of the character described; a plurality of joists; adjustable means for supporting said joists by their ends between parallel steel girders, said supporting means adapted to rest on the lower flange of a girder; a trough adapted to be supported under one of said girders; and adjustable means for supporting said trough; the adjustment of the joist supporting means and the trough supporting means with respect to the joist permitting raising or lowering of the joist while maintaining the position of the trough with respect to the lower flange of the girder the same.

In testimony whereof, I have hereunto set my hand this 27th day of November A. D. 1925.

EDWARD E. DAVIS.
